CUTTER BIT HOLDER

Sidney Ernest Proctor, Saunderton, High Wycombe, England, assignor to Austin Hoy and Company Limited, High Wycombe, England, a British company

Application June 27, 1957, Serial No. 668,386

Claims priority, application Great Britain June 27, 1956

5 Claims. (Cl. 262—33)

This invention comprises improvements in or relating to coal-cutter chains and equivalent pick-carrying devices.

In normal coal-cutter chains, the pick is secured by a setscrew and on conventional longwall working and certain types of semi-continuous mining machines, the pick is removed and turned 180° for reverse cutting. This procedure applies in majority of coal cutting in this country today and not only to chains, but also to other pick-carrying devices such as drums carrying picks. It is estimated that to change a pick in a cutter box averages about a minute which on coal-cutters employing up to one hundred pick boxes entails considerable time for this operation. The purpose of this invention is to reduce the time taken in changing picks.

It is a further object of the invention to provide means for picks on a coal-cutter chain or equivalent pick-carrying device to be gauged, i.e. set with their cutting edges projecting from the pick box by any desired amount.

According to one feature of the invention a coal-cutter chain or equivalent pick-carrying device has picks provided with shanks rotatably mounted in the pick-carrying boxes or like mountings and with means for locking them against rotation in one of at least two selected positions, for the purpose of enabling the pick to face in either direction of movement.

According to another feature of the invention the picks have shanks which are screw-threaded into the mountings and locking means are provided to lock the picks against rotation at several different positions representing different degrees of entry of shank into mounting. By this means the picks can be gauged as to the distance by which they stand out from the mountings and also if the locking means are appropriately designed the picks can be reversed.

According to a further feature of the present invention, in a coal-cutter chain or equivalent pick-carrying device having picks with shanks rotatably mounted in the mountings, locking means to lock each pick against rotation comprise an abutment on the inner end of the pick shank within the mounting, a spring-urged locking member within the mounting to engage said abutment and means affording access to said locking member for unlocking it, comprising an aperture through which a tool may be inserted.

The locking members may carry stems which extend upwardly through the centres of the pick shanks and the apertures be located in the picks themselves so that by inserting a tommy-bar into the side of a pick the locking member of that pick may be moved out of engagement with the said abutment and the pick rotated by moving the tommy-bar. This affords a very rapid means of reversal of the picks.

In a preferred construction according to the present invention the locking members are prevented from rotation by operation in non-circular bores in the mountings, which bores are continuations of screw-threaded bores in

which pick shanks are located, but the non-circular portions of the bores do not extend into the screw-threaded portion. If the non-circular bores are closed at their inner ends, this results in a construction which is sealed against access of dirt and dust by means of the screw-threaded shanks of the cutter picks, and such sealing is a valuable feature according to the present invention.

The following is a description by way of example of certain constructions in accordance with the invention, reference being made to the accompanying drawings in which:

Figure 1 is a section through a pick box in accordance with one construction of the invention, showing the cutter pick in side elevation;

15 Figure 2 is a front elevation of the pick removed from the box;

Figure 3 is a perspective view of the locking member removed from the box;

20 Figure 4 is a view similar to Figure 1 of an alternative construction showing the pick locked in position;

Figure 5 is a section upon the line 5—5 of Figure 4 looking in the direction of the arrows;

25 Figure 6 is a view of the same construction similar to Figure 4, but showing the parts in the unlocked position;

Figure 7 is a similar view to Figures 4 and 6, showing the parts with the pick adjusted outwardly;

30 Figure 8 is a plan of the pick box with the pick and adjustment members removed, so as to show the cross-section of the locking recess; and

Figure 9 is an underside plan view of a locking spring for use in the construction shown in Figures 4 to 8.

A coal-cutter chain with which the present invention is to be employed may have links of any desired or usual pattern which carry pick boxes. In the drawings the links are not shown but only the pick boxes upon them, which may of course be integral with the links in the usual manner. The pick boxes are drilled and screw-threaded at various angles relatively to the links to receive the shanks of cutter picks. The section, Figure 1, is taken in the plane of the centre of the pick and it will be understood that this plane may be at any desired angle relatively to the central plane of the coal-cutter chain.

45 Referring to Figure 1, the pick box 11 which constitutes the mounting for the pick is drilled out with a square-bottomed hole 12 which is screw-threaded as indicated at 13 to receive the shank 14 of a cutter pick 15 having an inserted tip 16 of hard metal. The screw-threaded shank 14 is cross-slotted as shown at 17 at its lower end and is drilled up axially with a hole 18 which extends from the slot 17 into the portion of the pick which projects out of the pick box and which meets a transverse aperture 19 drilled through the pick from side to side. In the hole 18 of the pick there can slide freely the shank 20 of a locking member which is shown in detail in Figure 3. The locking member at its lower end has a square portion 21 of the shank and between the square portion 21 and the round portion 20 there is

50 a circular collar 22 which carries a locking rib 23 adapted to enter the cross-slot 17 in the underside of the pick shank. A spring 24 surrounds the square shank 21 in the bottom of the drilled hole 12 and urges the collar 22 upwards. The square shank 21 slides in a square hole 25 in the bottom of the pick box. The upper end of the round shank 20 is rounded and is long enough to project upwardly into the cross-aperture 19 as shown at 26. If a tapered tommy-bar is inserted into the aperture 19 it will depress the end 25 of the shank 20 and carry the locking rib 23 out of the slot 17 in the shank of the pick. The pick can then be rotated either to reverse it or to adjust its gauge, and whether it is

55 60 65 70 75 80 85 90 95

left facing forward or aft on the chain when the tommy-bar is removed, the spring 24 will press the collar 22 upwards and the locking rib 23 will re-engage the slot 17 and prevent further movement of the pick.

This construction is simple and prevents entry of dust from the outside of the pick box because the hole 12 is sealed by the screw-thread 14. However, in some positions of the box 11 on the chain link there is a possibility of dust entering the hole 12 through the space allowed for the sliding movement between the square shank 21 and the aperture 25 in which it works. In order to obviate this possibility the construction shown in Figures 4 to 8 has been devised. In this construction the pick-box 11 is provided with a screw-threaded aperture 30 to receive a screw shank 14 of a cutter pick 15 similar to that already described for Figures 1 to 3. The screw-threaded aperture 30 of the pick 11 however, instead of extending nearly to the lowermost limit of the pick box, extends only part of the way therethrough and then has a shoulder 31 and is continued as a smaller aperture 32 having lateral key-shaped enlargements 33, 34 (see Figures 4 and 8). In the central hole 18 of the pick there slides the shank 35 of a locking member which has a transverse keying portion 36 to enter the locking slot 17 of the pick. The keying portion 36 of the locking member 35 has at its ends longitudinally projecting locking members 37 which enter the slots 33, 34 and are capable of sliding therein. Within the locking members 37 the shank 35 carries a spigot 38 which enters the upper end of a conical spring 39. The base of the spring 39 rests on a plate 40 which is welded to the underside of the pick box 11 and closes the lower end of the aperture 32. The upper end or nose 26 of the shank 35 enters the transverse aperture 19 in the pick, as already described. The nose 26 may be of smaller diameter than the main part of the shank 35 and joined thereto by a conical seating 41 which helps to keep out dust. As already explained, if a tommy-bar is inserted into the aperture 19 the nose 26 is depressed and it pushes the locking member 36 out of the slot 17 in the bottom of the pick and frees the pick for rotation. When the tommy-bar is removed, if the pick is facing directly fore or aft along the chain the locking member 36 is free to enter again the slot 17 in the pick under the influence of the spring 39 and to lock the pick against rotation.

The cage can be adjusted when the tommy-bar is inserted by unscrewing or screwing up the pick for one or more whole turns as shown in Figure 7, and on withdrawal of the tommy-bar 42 the locking element 36 will still lock the pick in a fore or aft direction. The tommy-bar 42 is shown in position in Figure 6.

The spring 39 shown in Figures 4 to 7 may be a plain conical spring or it may have its lower and larger turns flattened to fit into the key-shaped aperture 32, 33, 34, somewhat as shown at 52 Figure 12, if desired.

The construction described makes an extremely quick method of reversal of cutter picks; it is also a very safe method of locking because centrifugal force on the picks tends to hold the locking member in its locking position; the locking means is also protected from dust and dirt so that it is not likely to get out of order.

I claim:

1. In a coal cutter, the combination of a pick-box having a screw-threaded pick-supporting aperture therein, a pick having a cutter portion and a screw-threaded shank

adjustable by rotation in said aperture, a spring and a locking member in the aperture below the shank having a stem extending through the shank into the cutter portion, said spring normally biasing said locking member into engagement with said shank, the cutter portion having a transverse hole intersecting the axis of the stem so that on insertion of a bar the shank is unlocked, becomes rotatable by said bar into adjusted position and relocks on removal of the bar.

5 2. In a coal cutter, the combination of a pick-box having a screw-threaded pick-supporting aperture therein, a hole in the pick-box forming an extension of the screw-threaded aperture and having a non-circular portion, a pick with a cutter portion and a screw-threaded shank fitting in said screw-threaded aperture shaped to afford a locking abutment on the end of the shank, a locking member slideable in the non-circular portion of said hole and having a locking abutment adapted to co-operate with said locking abutment on the shank of the pick, a spring in said hole to urge the locking member towards the shank, and an unlocking extension on the locking member slideable through a hole in the pick-shank which extends into the cutter portion thereof, as far as a transverse hole through the cutter portion, to permit unlocking of the cutter pick, the locking abutments being symmetrical about the axis of the screw-thread to permit the pick to be locked in at least two positions and to engage the shank of the pick for more than one revolution thereof.

10 3. A pick-box assembly for a coal cutter as claimed in claim 2 wherein the non-circular portion of the said hole in the pick-box consists of a non-circular aperture at the bottom of said hole, of smaller cross-sectional area than the hole and the locking member has a non-circular stem slideable in said non-circular aperture, a collar upon the stem which carries the abutment to engage the locking abutment on the end of the shank of the pick and the unlocking extension on the locking member is a circular extension coaxial with the said shank and fitting therein.

15 4. A pick-box assembly for a coal-cutter as claimed in claim 2 wherein the non-circular portion of the hole in the pick-box comprises the main part of the length of said hole and is large enough to house the body of the locking member, the body of said locking member is made non-circular to fit said hole and is hollow, the spring extends into the hollow in the locking member and the bottom of the hole is completely closed.

20 5. A pick-box assembly, as claimed in claim 4, wherein the spring has a non-circular base to fit the hole in the pick-box and is tapered to enter the hollow in the locking member.
